UNITED STATES PATENT OFFICE.

SAMUEL J. HOEXTER, OF ANN ARBOR, MICHIGAN, ASSIGNOR TO ERNEST E. BELL, OF GLEN RIDGE, NEW JERSEY.

TRANSOM-OPERATOR.

1,165,411.

Specification of Letters Patent. Patented Dec. 28, 1915.

Application filed March 18, 1914. Serial No. 825,473.

To all whom it may concern:

Be it known that I, SAMUEL J. HOEXTER, a citizen of the United States, and a resident of Ann Arbor, county of Washtenaw, and 5 State of Michigan, have invented a certain new and useful Mechanical Movement Particularly Applicable to Transom-Operators, of which the following is a specification.

This invention relates to devices for operating transoms and other mechanism in 10 which it is desirable to have a considerable multiplication of power, and in which it is also desirable to have a positive lock, whereby when the source of power is removed, the 15 parts subjected to load will remain immovable in position. These and further objects will more fully appear from the following specification and accompanying drawings, considered together or separately.

20 Figure 1 is a view partly in section of a portion of a transom operator, with one embodiment of my invention applied thereto, the section being taken on the line 1—1 of Fig. 2. Fig. 2 is a side view of the same, 25 partly in section, the section being taken on the line 2—2 of Fig. 1. Fig. 3 is a view of the operating parts of a portion of my device in one position. Fig. 4 is a similar view of the parts in another position. Fig. 5 is 30 a similar view of the parts in still another position. Fig. 6 is a sectional view taken on the line 6—6 of Fig. 3. Fig. 7 is a view similar to Fig. 3 of a modification. Fig. 8 is a section on the line 8—8 of Fig. 7. Fig. 35 9 is a view similar to Fig. 3 of still another modification. Fig. 10 is a similar view of still another modification. Fig. 11 is a view on the line 11—11 of Fig. 10. Fig. 12 is a view similar to Fig. 3 of still another modification.

40 In all of the views, like parts are designated by the same reference character.

Figs. 1 and 2 represent my invention applied to a transom operator. In the drawings, *a* represents the transom, *b* the frame, *c* 45 the crank connected to the transom, and by means of which it is opened and closed, *d* a link connected to the crank, *e* a rod mounted in suitable guides so as to be capable of vertical movement. This rod is connected 50 to the link *d*. *f* is the case containing the mechanism for moving the rod and *g* the handle protruding from the case, and by means of which the mechanism is operated.

55 Figs. 5 to 12 inclusive represent the particular mechanism for actuating the rod *e*

through a toothed member which may be the rack of Figs. 1 to 9 or the wheel of Figs. 10 to 12. *1* represents the axle or shaft. On this shaft are a plurality of eccentrics 2. Associated with each eccentric is an arm 3. 60 On one side of the arm is a notch or slot 5. *6* is a pin lying within the notch or slot. *7*, *7* are plates on each side of the arms of the eccentrics. Two plates are connected together by the pin *6*. Other fastenings, as 65 shown in Fig. 2, may be employed, so that the case *f* is produced. The eccentrics are preferably symmetrically arranged or disposed, as shown in Fig. 3. They are preferably of the same size, and have the same degree of eccentricity. I prefer to make the shaft, where it engages with the eccentric, of polygonal cross-section. By making it of this shape, with as many sides or multiples thereof as there are eccentrics, and having 70 the openings in the eccentrics of the same shape, they may be threaded on the shaft, and will automatically dispose themselves in symmetrical relation. This simplifies the assembling operation, and makes the arrangement of the eccentrics exact. The number of teeth on the arms depends upon the 75 circumstances. In connection with the mechanism described, is a toothed member 8. This toothed member has a face as broad as the combined width or thicknesses of all the arms. In Figs. 3, 4 and 5, the toothed member 8 is a rack. It is supported in suitable guides within the case *f*, so that it will be maintained at a definite distance from the 80 shaft 1. 85

The operation of the device is clearly shown in Figs. 3, 4 and 5. Let it be assumed that the shaft 1 rotates in the clockwise direction shown; then the toothed part of each arm will successively engage with the toothed part of the member 8, and move the latter downward in the direction indicated by the arrow. The pin 6 and notch or slot 5 prevents the arms from rotating, and 95 compels the toothed portions of the arms to move through an ellipse with its greatest axis in a vertical plane. The teeth on the arm, therefore, come in contact with the teeth on the member 8, and engage with these teeth and move the member 8 in the direction in which the arm is being moved, and then will release themselves from engagement with the teeth on the member 8. Before this occurs, however, the teeth on 100 105 110 115

the next arm 3 will have been brought into engagement with the teeth on the member 8. Therefore, it is necessary to have enough eccentrics, and to so arrange the parts that 5 one toothed arm 3 will always be in engagement with the toothed member 8. Figs. 7 and 8 show the invention applied to four arms and four eccentrics. Fig. 9 shows an arrangement in which the slot 5 is located 10 between the eccentrics and the toothed parts of the arms. Figs. 10 and 11 show the application of the invention to a structure in which the toothed member 8 is the rim of a wheel with the rod *e* attached thereto. According to this embodiment of the invention, 15 the teeth are formed on the internal rim of the wheel. Fig. 12 shows the invention embodied in connection with the external rim of a wheel.

20 One very important feature of the invention particularly applicable to transom operators is that the member 8 remains locked in position, when power is taken from the shaft 1, irrespective of the load upon the 25 member 8. This may be attributed partly to the frictional engagement of the peripheries of the eccentric with the arms. This locking effect is also increased by the frictional retardation of the slot 5 upon the pin 30 6; also it is partly caused by the frictional engagement of the teeth on the arm engaging with the teeth on the member 8. There is a great deal less friction when the apparatus is being operated than there is with 35 the worm-gear. This I attribute to the fact that the application of power is in the same plane with the impressed motion.

40 The device is also very much cheaper to make than a worm-gear, for the reason that the eccentrics and arms may be stamped out of sheet metal.

45 All of the eccentrics and all of the arms being alike, and with the shaft of the shape described, the parts are very easily assembled without danger of mis-alinement.

50 In accordance with the provisions of the patent statutes, I have described the principle of my invention, together with the apparatus which I now consider to represent the best embodiment thereof; but I desire to have it understood that the apparatus shown is merely illustrative and that the invention 55 may be carried out in other ways.

Having now described my invention, what I claim as new and desire to secure by Letters Patent, is:—

60 1. In a transom lifter, the combination of a rotary member carrying a plurality of eccentrics, an arm associated with each eccentric, a fixed guide associated with each arm, a gear tooth on each arm, in combination with a second member also having gear teeth and adapted to be acted upon by said arm teeth in succession by the rotation of the 65 first member and a transom shifting member

operatively connected to said second member.

2. In a transom lifter, the combination of a rotary member carrying a plurality of eccentrics of uniform size and symmetrically disposed, an arm associated with each eccentric, a fixed guide associated with each arm, a gear tooth on each arm, in combination with a second member also having gear teeth and adapted to be acted upon by said arm teeth in succession by the rotation of the 70 first member and a transom shifting member operatively connected to said second member.

3. In a transom lifter, the combination of a rotary member carrying a plurality of eccentrics, an arm associated with each eccentric, each arm having a notch, a pin within all of the notches, a fixed guide associated with each arm, a gear tooth on each arm, in 75 combination with a second member also having gear teeth and adapted to be acted upon by said arm teeth in succession by the rotation of the first member and a transom shifting member operatively connected to 80 said second member.

4. In a transom lifter, the combination of a rotary member carrying a plurality of eccentrics of uniform size and symmetrically disposed, an arm associated with each eccentric, each arm having a notch, a pin within 95 all of the notches, a gear tooth on each arm, in combination with a second member also having gear teeth and adapted to be acted upon by said arm teeth in succession by the rotation of the first member and a transom shifting member operatively connected to 100 said second member.

5. A transom operator, which comprises a rotary member carrying a plurality of eccentrics, an arm associated with each eccentric, a fixed guide associated with each arm, a gear tooth on each arm, in combination with a second member, and a connection between the second member and the transom, 105 said second member having gear teeth adapted to be acted on by said arm tooth in succession by the rotation of the first member.

6. A transom operator, which comprises a rotary member carrying a plurality of eccentrics of uniform size, and symmetrically disposed, an arm associated with each eccentric, a fixed guide associated with each arm, a gear tooth on each arm, in combination with a second member, and a connection between the second member and the transom, 115 said second member having gear teeth adapted to be acted on by said arm tooth in succession by the rotation of the first member.

7. A transom operator, which comprises a 125 rotary member carrying a plurality of eccentrics, an arm associated with each eccentric, each arm having a notch, a pin within all of the notches, a gear tooth on each arm, in combination with a second member, and a 130

connection between the second member and the transom, said second member having gear teeth adapted to be acted on by said arm tooth in succession by the rotation of the 5 first member.

8. A transom operator, which comprises a rotary member carrying a plurality of eccentrics of uniform size, and symmetrically disposed, an arm associated with each eccentric, each arm having a notch, a pin within 10 all of the notches, a gear tooth on each arm, in combination with a second member, and a connection between the second member and the transom, said second member having 15 gear teeth adapted to be acted on by said arm tooth in succession by the rotation of the first member.

9. A transom operator which comprises a shaft of polygonal cross-section, having

sides equal in number to or multiples of the 20 eccentrics, a plurality of eccentrics, each having an opening of the same shape as the cross-section of the shaft, said eccentrics being symmetrically disposed on said shaft, an arm associated with each eccentric, a fixed 25 guide associated with each arm, a gear tooth on each arm, in combination with a second member, and a connection below the second member having gear teeth, adapted to be acted 30 on by the teeth of the various arms in succession by the rotation of the shaft.

This specification signed and witnessed this second day of March, 1914.
